Primary Examiner — Lauren D McVey(74) *Attorney, Agent, or Firm* — Moore & Van Allen PLLC; Henry B. Ward, III(57) **CLAIM**

The ornamental design for an insulator, as shown and described.

DESCRIPTION

FIG. 1 is a perspective view of an insulator, showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a side elevation view thereof; and,

FIG. 7 is an opposite side elevation view thereof.

The broken lines shown in FIGS. 1-7 illustrate portions of the insulator that form no part of the claimed design.

The wire frame lines shown throughout the views are intended to indicate surface contour.
